DESIGN FOR AN AUTOMOBILE

Vahan Hagopian, New York, N. Y.

Application June 23, 1934, Serial No. 52,309

Term of patent 7 years

To all whom it may concern:

Be it known that I, Vahan Hagopian, a citizen of the United States, residing at 40 East 49th Street, New York, in the county of New York and State of New York, have invented a new, original, and ornamental Design for an Automobile, of which the following is a specification, reference being had to the accompanying drawing, forming part thereof.

Fig. 1 is a side elevational view of an automobile, showing my new design.

Fig. 2 is a top plan view, and

Fig. 3 is a front elevational view.

I claim:

The ornamental design for an automobile, as shown.

VAHAN HAGOPIAN.
